H. B. KIPPER

PROCESS OF AND APPARATUS FOR DISTILLATION OF OIL FROM OIL SHALE

Filed Aug. 2, 1923

UNITED STATES PATENT OFFICE.

HERMAN B. KIPPER, OF MUSKEGON, MICHIGAN.

PROCESS OF AND APPARATUS FOR DISTILLATION OF OIL FROM OIL SHALE.

Application filed August 2, 1923. Serial No. 655,163.

The recovery of oil from shale has been carried on successfully for a considerable period in Scotland. In the United States, although large shale deposits exist in many States and possibly some commercial operations have been conducted, no extensive recovery of oil from shale has ever been established. The fact that only about 20% of oil can be recovered from the shale, of course, renders commercial competition or recovery difficult against petroleum well recovery, even though the oil may have to be pumped from considerable depths. On the other hand, it is my contention that the chief difficulty that confronts the recovery of the oil from natural shales is not due to their low oil content, but rather to the fact that the requisite stills or apparatus of necessary efficiency has not existed.

The object of my invention is, therefore, to provide an apparatus, whereby I can carry out my new process of distillation of oil from shale, which consists in that the shale is first finely ground, then fed to a heated still or converter in which, while being fed therethrough, it is treated by revolving hammers, which keep it from "caking" and possibly grind it even finer. The ground organic residue together with the distillation products are then passed into an externally heated dust or separation chamber from which the inorganic material and distillation products are subsequently drawn off and the latter condensed in either a direct or indirect condenser.

The apparatus for carrying out this process is illustrated diagrammatically in the accompanying drawing in which similar reference characters denote corresponding parts, and in which Fig. 1 is a longitudinal section of the apparatus and Fig. 2 a cross section on line 2—2 of Fig. 1.

The still or converter comprises a drum or cylinder A, which is connected to a furnace B through flues C, C'. Heavy fuel furnishes heat, preferably as a producer gas to the furnace. Centrally mounted in the converter is a rotary shaft D which may be driven through gears d , d' , and a driven shaft d^2 from a suitable source. The shaft D is hollow to form passages D' for water for cooling purposes. Externally this shaft is suitably insulated as at D² the major part of its length, the insulation D² being preferably enveloped by a metal covering D³.

Fixed on the shaft D at intervals are metal discs E supporting longitudinal rods F from which by means of iron bars G are suspended guiding hammers G' extending longitudinally through the apparatus and 60 preferably bevelled, so as to offer less resistance to the material contained in the converter A. The end walls or heads H, H' of the cylinder are rotatively mounted but not rigidly connected to cylinder A and 65 are operatively connected to a driven shaft I. These end walls or heads H, H' are slowly rotated and carry a set of preferably bevelled bars K, which travel near the interior wall of A and serve to prevent 70 "caking" of the material.

The shale, after being finely ground, is charged into the converter A through a spiral conveyor L or other means. While it is being fed through the converter, it is 75 treated by the hammers G' revolving with great speed, several hundred revolutions per minute. Thereby the shale is ground to a finer degree and by being constantly stirred is prevented from "caking," while the distillation of the oil occurs with great rapidity.

I have employed distillation temperatures of 300° to 500° C., but there is no reason why a somewhat wider range of temperatures 85 might not be employed, such as 700° C., dependent on the character of the shale. External heat may also be employed to the converter A or the latter may be merely insulated. After the requisite reaction temperature has been reached air alone, or a mixture 90 of air and other heated gases, may be passed into cylinder A. The heated gases pass through the spray of oil shale in the cylinder. The heat of combustion of the oil 95 shale then tends to maintain the necessary distillation temperature throughout the apparatus.

M denotes a discharge passage leading 100 from the cylinder A into a dust or separation chamber N. The latter is insulated or externally heated as at N', in any suitable manner. The chamber N is provided with a discharge passage O, which may have a helical worm O' and which serves to lead 105 off the inorganic material. It is also provided with a passage P through which the distillation products may be drawn off by suction and conveyed to a suitable condenser 110 Q in which it may be condensed.

The grinding hammers used may be shaped in any suitable manner.

Since the apparatus and the parts thereof may be modified in various ways, for instance several shafts with hammers might be used in place of one, without departing from the principle of my invention, I do not wish to restrict myself to any of the details described and shown.

10 The process and apparatus has also been successfully used for the distillation of the by-products from coal. In the case of oil shale, I have mostly employed finely ground stone and oil, thoroughly mixed and compressed and which I call "artificial shales".

As noted there are two sets of bevelled bars extending longitudinally through cylinder A. One set is supported from the rotatable heads. The other set is carried from rods F by means of intermediate metal pieces G. The flat sides of bevelled bars K lie approximately at a right angle to a line drawn to the center of shaft D, whereas the flat sides of bevelled bars G' lie approximately at an angle of 45° to a similar line. In the first case the edges of bevelled bars K cut away any adhering material from the wall of A, whereas in the second case bevelled bars G' act as hammers or beaters of the reaction material. The outer ends of the flat bars G' are also bevelled at an angle of approximately 45° to the axis of the driving shaft, so as to offer little resistance to the material contained in the cylinder A.

What I claim and desire to secure by Letters Patent is:-

1. In a process of distillation of the oil constituents from oil shale in a closed chamber, the step of passing heated gases through the finely ground oil shale to produce distillation of the organic constituents of the shale, the step of simultaneous mixing and further subdividing of the shale and the step of removing the material from the walls of the distillation chamber.

2. In a process of distillation of the oil constituents from oil shale in a closed chamber, the step of passing heated gases through the finely ground oil shale to produce partial combustion of the organic constituents of the shale, the step of simultaneous mixing and further subdividing of the shale

and the step of removing the material from the walls of the distillation chamber.

3. In a process of distillation of the oil constituents from oil shale, in a closed chamber at the temperature of 300° to 700° C., the step of passing heated gases and air through the finely ground oil shale to produce partial combustion of the organic constituents of the shale, the step of simultaneous mixing and further subdividing of the shale and the step of removing the material from the walls of the distillation chamber.

4. In the herein described process of distillation of the organic constituents from shale in a closed chamber having openings and outlets for gases and solid materials at the temperature of 300° to 700° C., the step of feeding the finely ground shale to said chamber, the step of passing heated gases and air through the finely ground oil shale to produce partial combustion of the organic constituents of the shale, the step of simultaneous mixing and further subdividing of the shale, the step of removing the material from the walls of the condensation of the distillation products and the removal of the residual inorganic products through the lower exit of the distillation chamber.

5. In an apparatus for carrying out the herein described process of distillation, a chamber heated by the passage of highly heated gases and by air which produces partial combustion of the organic constituents passing through said chamber, rapidly revolving hammers therein adapted to simultaneously mix and subdivide the material fed through said chamber, said hammers being in the form of longitudinally extended flat bars, the outer edges of which are bevelled, a central rotary hollow internally cooled shaft extending longitudinally through said chamber and from which said hammers are suspended, a second set of bevelled bars located near the internal periphery or wall of said chamber, and rotatable heads closing the ends of said distillation chamber and carrying said second set of bars, the latter being adapted to remove the material from the walls of said chamber.

In testimony whereof I affix my signature.

HERMAN B. KIPPER.
